United States Patent Office

Des. 194,881
Patented Mar. 26, 1963

194,881

SWATHER

Constantine J. Kermes, Lancaster, Pa., and Allen A. White, Peabody, and Richard E. Ten Eyck, Wichita, Kans., assignors to Sperry Rand Corporation, New Holland, Pa., a corporation of Delaware

Filed May 12, 1961, Ser. No. 65,140

Term of patent 14 years

(Cl. D40—1)

FIG. 1 is a front perspective view taken from the left side of a swather embodying our new design;

FIG. 2 is a perspective view taken from the left side thereof; and

FIG. 3 is a perspective view taken from the right side thereof.

The essential features of our design reside in the full-line portions of the drawings.

We claim:

The ornamental design for a swather, as shown and described.
